PLIERS

Anthony L. Vissat, Pittsburgh, Pa.

Application November 17, 1943, Serial No. 510,833

1 Claim. (Cl. 81—50)

This invention relates to an improved pair of pliers, and important objects and advantages thereof are to provide a tool of the character described, which embodies a pair of associated jaws having the opposed working faces thereof in parallel relation to each other throughout the latitude of travel of said jaws, which will squarely hold or grip any object engaged thereby, which operate to exert exceptional gripping force, which includes means for automatically locking the embodied jaws when resistance is exerted to the latter and for limiting the movement of the jaws to the open positions, which is simple in its construction and arrangement, durable and efficient in its use, compact, conveniently operable, and comparatively economical in its manufacture.

To the accomplishment of these and such other objects as may hereinafter appear, the invention resides in the novel construction, combination, and arrangement of parts herein specifically described and illustrated in the accompanying drawing, but it is to be understood that the latter is merely illustrative of an embodiment of the invention, and that changes in the form, proportions, and details of construction may be resorted to that come within the scope of the claims hereunto appended.

In the drawing wherein like numerals of reference designate corresponding parts throughout the several views:

Figure 1 is a front elevational view of a pair of pliers, with portions cut away and in section, constructed in accordance with the invention.

Figure 2 is a rear elevational view of the pliers.

Figure 3 is an edgewise view thereof.

Figure 4 is a front view of the sliding jaw embodied in the invention.

Figure 5 is an edgewise view of the sliding jaw.

Referring in detail to the drawing 1 and 2 respectively denote a pair of operating handles, which are pivotally joined together at their forward ends by a pivoting bolt 3, or in any other suitable manner.

The handle carries an integrally formed fixed jaw 4 which includes a projecting jaw plate 5 having its forward edge 6 disposed at right angles to the inner or working face of said fixed jaw. A guide groove 7, having an open front side and a stepped bottom, as indicated at 22, is formed in the fixed jaw and extends or continues along the forward margin of the plate edge 6.

A sliding jaw 8 opposes the fixed jaw 4 and is provided with an integrally formed guide shank 9, which latter projects at right angles to the inner working face of the associated jaw 8. The thick-

ness of the shank 9 is less than the thickness of the sliding jaw, and thereby provides a seating edge 10 at the base of the latter. The juncture of the sliding jaw 8 with the guide shank 9 is strengthened by a reinforcing cheek 24, which is disposed on the front face 25 of said shank 9 and on the adjacent lower portion of the sliding jaw 8.

The guide shank 9 has a stepped rear face, as indicated at 23, conforming to the contour of the stepped bottom 22 of the guide groove 7, and is slidably engaged in the latter, as clearly illustrated in Figure 3, whereby said stepped face and bottom interengage each other. A relatively short locking lug 9' is formed on the rearward edge 12 of the shank 9 at the free end of the latter. The plate edge 6 is engaged against the seating edge 10 at the base of the sliding jaw 8, and the locking lug 9' is the only portion of the edge 12 that engages the rear wall 13 of the guide groove 7, for the purpose to be described and as clearly illustrated in Figures 1 and 2. Such assembly of the jaws allows the sliding jaw to shift freely toward or away from the fixed jaw, and maintains the parallel positions of the inner faces of said jaws throughout the latitude of travel of said sliding jaw.

The opposed working faces of the jaws 4 and 8 are preferably formed with transversely disposed teeth for the obvious purpose of augmenting their gripping action on pipe or other round stock. The jaws may further be provided with opposed angular recesses 11 to better adapt same for engaging polygonal-shaped objects.

The sliding jaw 8 is adjusted by the movement of an enlarged head 14 which is formed integral with the operating handle 2. A compensatory cam slot 15 is provided at the forward end and to one side of the enlarged head for engaging a stud pin 16. The latter is fixed in the front face 25 of the guide shank 9 adjacent to the free end of the latter, and extends through the cam slot 15. The enlarged head portion 26, which overlaps the reinforcing cheek 24, is suitably recessed on its inner surface to provide clearance for said cheek 24. The construction and pivotal connection of the handles 1 and 2 is such as to provide the conventional operation, whereby when said handles are drawn toward each other the sliding jaw 8 will shift toward the fixed jaw 4, and when the handles are separated the jaws are also parted or released.

The enlarged head 14 is positioned flatly against the front face of the guide shank 9, and is of ample area to suitably maintain the proper as-

sembly of the sliding jaw 8 with the fixed jaw 4, but all stresses to which the sliding jaw may be subjected are borne by the guide shank 9 due to the interengagement of the latter in the guide groove 7 in the manner herein set forth.

An adjusting bolt 17 is threadedly engaged in the jaw plate 5 and is operable to project the end thereof through the rear wall 13 of the guide groove 7 into the latter. When so projected said end provides a rest for the rearward edge 12 of the guide shank 9 and provides a slide alignment with the engaging face of the locking lug 9'. Further, when the bolt 17 is so projected the sliding jaw 8 will not lock in any adjusted position, and said sliding jaw may be freely adjusted by the manipulation of the operating handles 1 and 2.

When the adjusting bolt 17 is retracted within the groove wall 13 to disengage the rearward edge 12 of the guide shank 9 from said bolt 17, the jaws 4 and 8 may readily be adjusted relatively to each other by the usual manipulation of the operating handles 1 and 2. However, any stress exerted on the jaws by work engaged between and tending to open the latter will immediately impart a locking action to the guide stem 9 by allowing and causing the inner sharp corner 20 of the locking lug 9' to engage on the groove rear wall 13, and the diagonally opposed sharp corner 21 to engage on the outward wall of the guide groove 7. This locking action is an important feature of the invention and serves to auto-

matically lock the sliding jaw 8 in any and all possible adjusted positions of the latter.

The jaw plate 5 and the enlarged head 14 are each provided with a cutter notch, respectively indicated at 18 and 19, which coact to serve as a cutter for severing wire, nails and the like, in the usual well known manner.

The present invention provides a most efficient device of its kind, which may be economically manufactured and successfully employed in the manner herein set forth.

What I claim is:

A pair of pliers of the character described comprising the combination of a pair of pivotally joined operating handles, a fixed jaw formed integral with one of said pair of handles and including a jaw plate provided with a guide groove, a sliding jaw provided with an integrally formed guide shank extending at right angles thereto, said shank having a shiftable engagement in said groove, an enlarged head formed integral with the other of said pair of handles and being operatively joined with said shank to adjust said sliding jaw with respect to said fixed jaw, a locking lug carried on the rearward edge of said shank at the free end of the latter for engaging a side wall of said groove to hold said sliding jaw in the adjusted position, and an adjusting bolt threadedly engaged in said plate and being projectable into said groove to engage said shank for preventing the operation of said locking lug.

ANTHONY L. VISSAT.
